Primary Examiner — Karen S Acker*Assistant Examiner* — Omeed Agilee(74) *Attorney, Agent, or Firm* — Shumaker, Loop & Kendrick, LLP; James D. Miller(57) **CLAIM**

The ornamental claimed design for a spray bulb cleaner for digital camera sensors, as shown and described.

DESCRIPTION

FIG. 1 is a front perspective view of the spray bulb cleaner for digital camera sensors showing my new design;

FIG. 2 is a top perspective view of the spray bulb cleaner for digital camera sensors of FIG. 1;

FIG. 3 is a bottom perspective view of the spray bulb cleaner for digital camera sensors of FIG. 1;

FIG. 4 is a bottom plan view of the spray bulb cleaner for digital camera sensors of FIG. 1; and,

FIG. 5 is an elevational view of the spray bulb cleaner for digital camera sensors of FIG. 1.

The broken lines showing a nozzle opposite the conical foot portion and the main body disposed there between depict portions of the spray bulb cleaner for digital camera sensors that form no part of the claimed design.
